UNITED STATES PATENT OFFICE.

FRANK H. BICKFORD, OF DAYTON, OHIO, ASSIGNOR TO THE NATIONAL CASH REGISTER COMPANY, OF JERSEY CITY, NEW JERSEY, A CORPORATION OF NEW JERSEY.

CASH-REGISTER.

SPECIFICATION forming part of Letters Patent No. 690,554, dated January 7, 1902.

Application filed March 31, 1900. Serial No. 11,155. (No model.)

To all whom it may concern:

Be it known that I, FRANK H. BICKFORD, a citizen of the United States, residing at Dayton, in the county of Montgomery and State 5 of Ohio, have invented certain new and useful Improvements in Cash-Registers, of which I declare the following to be a full, clear, and exact description.

My invention relates to improvements in 10 cash-registers. Its use is not restricted to any kind or type of machine; but for purposes of illustration I have shown it as applied to a cash-register of the type patented to Cleal and Reinhard on April 13, 1897, No. 580,378.

One object of my invention is to provide 15 against fraudulent operation of the machine.

In many cash-registers the crank or other operating means is normally locked until after a special or department key is pressed.

20 In some of such machines owing to the difficulty of properly adjusting the mechanism it is possible to unlock the crank or other operating means before the special key has been pressed fully in, so that persons wishing to

25 defraud the machine have resorted to the practice of pushing the special key almost but not quite in—that is, far enough to release the crank—then starting the crank, and by removing the finger from the special key per-

30 mit it to spring back to normal position, whereby the machine can be operated without leaving any record of the person operating it. Especially is it important to prevent such fraudulent manipulation in machines of the type

35 shown in the drawings, in which when certain classes of sales—for example, "Charge," "Rec'd on acc't," or "Paid out" sales—are to be registered the cash or totalizing counter is arranged to be thrown out of connection

40 with the registering mechanism.

In the accompanying drawings, forming part of this specification, Figure 1 represents a central vertical section, partly broken away, through the cash - register of the class described and having my improvement applied thereto; and Fig. 2 represents a detail elevation, partly broken away, showing the operating-crank and the gearing usually provided

for the machine shown in said patent and in Fig. 1. 50

In the drawings the numeral 1 designates the fixed frame of the machine; 2, the operating-crank; 3, the special keys; 4, the main rock - shaft, and 6 operating-segments fast upon the rock-shaft. When the crank is 55 turned, the power is transmitted, through intermediate gears 25, to the rotation-shaft 26, from which in turn motion is transmitted, through the link 27, to operate the rock-shaft. Under this construction whenever the operating-crank is turned the operating-segments 60 6 (of which only one is shown) are rocked downward and then up again. A toothed registering-segment 28 is journaled upon the rock-shaft 4 and drives the intermediate gear 65 29, which in turn drives a small intermediate gear 30, which is journaled upon the same shaft as the registering-wheels and registering-gears. To the left-hand side of the smaller intermediate gear 30 is riveted or otherwise secured a third gear 31. (Shown in broken lines.) A complete and detailed description of this 70 part of the machine may be had by reference to the Cleal and Reinhard patent before referred to. It is therefore sufficient for present purposes to say that journaled on the same shaft and side by side with the gear 31 is one of the registering gear-wheels. (Not shown.) It is of exactly the same size as the gear 31, and secured to it is one of the registering- 75 wheels. Journaled upon the upper end of the pivoted vertical lever or frame 32 are idle pinions 33, (only one of which is shown,) which are normally disengaged. When the machine is operated to record a special transaction— 80 that is, when it is operated in connection with any one of the special keys 3—the registering gear-wheel and the gear 31 remain disengaged in a manner well known in the art, so that the counting or registering wheels are not 85 moved at all; but in the normal operation of the machine when a cash sale is recorded after the crank 2 has moved a certain distance from normal each idle pinion is rocked rear- 90 wardly into engagement with both the regis- 95 tering gear-wheel and the gear 31, thereby

connecting the two gears and bringing it about that movement is transmitted from the segments 28 to the registering-wheels, as shown in said patent to Cleal and Reinhard.

5 A reciprocating link 34 has a slotted rear end which straddles the rotation-shaft 26, upon which is a box-cam 35, in the cam-groove of which travels a stud 36. (Shown in broken lines.) In its lower edge and near its front 10 end the reciprocating link has a vertical slot through which normally passes a pin 37, secured to the lower end of the pivoted lever or frame 32. From this construction it will be readily understood that the pinion is rocked 15 into engagement with the gears 30 and 31 whenever the crank is turned. Whenever a special transaction is to be recorded, however, means are provided for lifting the front end of the reciprocating lever, so as to disconnect 20 it from the pinion-carrying frame, and thereafter when the crank is turned the pinion will not be rocked rearward, and consequently no connection will be established between the gear 31 and its registering gear-wheel, and 25 although the toothed segment 28 and the gears 29 and 30 will move as usual their movement will not be transmitted to the registering-wheels, as will be readily understood. When a special transaction is to be recorded, 30 the registering gears and wheels are "thrown out" or prevented from being brought into connection with the intermediate gears 30 by means of the upwardly and forwardly extending throw-out lever 17, which is fast upon the 35 horizontal rock-shaft 16 in a manner to be presently explained.

Only one bank of keys is shown in the drawings, and of this the six upper keys are amount or value keys, while the three lower keys are 40 for recording special or department transactions. Each of the latter is provided with a laterally-extending stud or pin 7, which is arranged to engage the inclined walls of the angular recesses 9 of the latch-plate 10. The 45 latch-plate through its arm 11 is journaled upon the shaft 12, so that whenever a special key is operated, as will be readily understood, the latch-plate will be swung upward and rearward. When one key is operated, the 50 hooks 13 of said plate are moved under the pins of the unoperated keys, and thus lock the latter. Pivoted at its front end to the latch-plate is a link 14, which at its rear end is pivoted to a short crank-arm 15, fast upon 55 the rock-shaft 16, so that the operation of a special key rocks the shaft 16 and brings the upper end of the throw-out lever 17 against the under side of the reciprocating link 34, thereby raising the latter to throw out the 60 registering-wheels, as already described. A spring 21 connects the throw-out lever with the frame and tends normally to pull the throw-out lever to its normal position, as shown in Fig. 1. There is also fixed upon 65 the rock-shaft 16 a locking-arm 19, (shown in broken lines,) upon the right-hand side of

which is secured a lug 19^a, having a beveled front face. The lug is normally just in front of an arc-shaped locking-flange 20, which is secured to the left-hand side of the operating- 70 segment 6. The lower end of the flange is beveled on its rear side, as shown at 6^a.

Under the construction just described as one of the special keys is depressed the locking-lug 19 passes under the lower end of the 75 flange 20 and comes to rest with its beveled face 19^a under the beveled end 6^a of said flange. While the lug is fastened under the flange the crank cannot be operated, for the reason that if it were started the lower end 80 of the flange would immediately strike against the locking-lug and the handle could be moved no farther. The depressing of the special key also swings the throw-out lever rearward against the front end of the reciprocating 85 link, but not far enough to disengage said link from the pinion-frame 32. When now, however, the crank is started after the special key is fully depressed, the operating-segment begins to swing downward and the bevelled face of its flange striking the beveled face 19^a of the locking-lug swings the latter rearwardly behind the flange 20 and holds it there until the operating-segment returns to its upper position, when the spring 21 draws 90 the throw-out lever, and consequently the latch-plate, forward to normal position. As stated, the initial movement of the crank swings the locking-arm 18 rearward, thereby rocking the shaft 16 and consequently swinging the throw-out lever farther under the reciprocating link 34, and thereby entirely disengaging the latter from the pinion-frame 32. It results from this construction that the crank or operating member cannot be started 95 until the special key is fully depressed, and when so depressed it is caught and held by its own detent, (not shown;) but it is also held within the angular slot 9 of the latch-plate, because the latter is locked and held in 100 its rearmost position whenever the lug 19 is held behind the locking-flange 20. The operation of throwing out the registering-wheels under this construction is not dependent upon the force which may be applied to the special 105 key operated, as the key simply sets the throw-out lever in position and the initial operation of the crank then performs the work.

It will be readily understood that my invention is equally adapted for application to 110 machines of other types than that shown in the drawings. For example, in those machines in which each bank of keys is replaced by an index or lever which is moved to different positions according to the transaction 115 or amount to be registered such lever may be arranged when in certain positions to set the throw-out lever 17, and then the actuation of the operating mechanism will complete the "throw-out" operation, as in the particular embodiment of my invention herein described.

Having thus described my invention, I claim as new and desire to secure by Letters Patent—

1. In a cash-register, the combination with 5 a series of keys, of a latch plate or lever arranged to be struck by the keys, a register-operating mechanism, and means connecting with the latch plate or lever and arranged to be thrown into position to lock the operating 10 mechanism during the time the operated key is moving from normal to its final operated position.

2. In a cash-register, the combination with an operating mechanism, of a special key, a 15 counter-throw-out mechanism, means operated by the key for setting said throw-out mechanism for operation in connection with the operating mechanism and devices connected to the operating mechanism for moving 20 the said setting means to lock the operated key.

3. In a cash-register, the combination with 25 a series of keys, of a register-operating means, mechanism controlled by the keys for locking the operating means after the initial movement of a key and until a key is fully operated, and actuated by the operating means to lock the operated key.

4. In a cash-register, the combination with 30 a series of keys, of a register-operating means carrying a locking projection, a movable member operated by the keys and carrying a locking projection which coöperates with the first-mentioned projection to lock the operating 35 means until a key is fully operated, and is operated by said first-mentioned projection to lock the keys.

5. In a cash-register, the combination with 40 a series of keys having projecting pins, of a plate having notches coöperating with said pins, a movable member carrying a locking-flange and a pivoted lever connected to said plate and having a locking-lug which coöperates with said flange whereby the plate is 45 moved to lock the keys.

6. In a cash-register, the combination with 50 a series of keys, of a plate common to said keys, a movable member carrying a beveled flange and a locking-block operated by said plate and coöperating with said flange so as to be operated by the same.

7. In a cash-register, the combination with 55 a series of keys, of an operating means having a beveled flange, devices set by the keys to be operated by said flange to lock the keys, and a register-controlling device actuated by said devices.

8. In a cash-register, the combination with 60 a series of keys, of an operating means having a beveled flange, a plate common to and operated by the keys, and devices connected to said plate and arranged to coöperate with the flange and be actuated thereby to move said plate and thereby lock the keys.

9. In a cash-register, the combination with 65 a series of keys, of an operating means, a plate

common to the keys and connections arranged to be set by the plate so as to be actuated by the operating device and when so actuated to move the plate to lock the keys. 70

10. In a cash-register, the combination with a series of keys, of an operating means carrying a beveled flange, a plate common to the keys and connections arranged to be set by the plate so as to be actuated by the flange 75 and when so actuated to move the plate to lock the keys.

11. In a cash-register, the combination with a series of keys, of an operating means provided with a beveled flange, a register and 80 throw-out devices, a rock-shaft carrying a lever for operating the throwing-out devices and a lug which coöperates with said flange, and a plate coöperating with the keys and connected to said rock-shaft. 85

12. In a cash-register, the combination with a series of keys, of operating means provided with a flange having a bevel-face, a register and throw-out devices, a rock-shaft moving a lever for operating the throwing-out devices 90 and having an arm provided with a stop-lug which is arranged to coöperate with said flange, a plate having detent-hooks for said keys and arranged to be operated by the latter and means connecting the rock-shaft and 95 plate.

13. In a cash-register, the combination with a series of keys, of register-operating means, a movable member operated by the keys to first lock and then unlock or release the operating devices, and means actuated by the operating means to impart an additional movement to the movable member and thus cause it to lock the keys. 100

14. In a cash-register, the combination with 105 a series of keys, of register-operating means, a movable member operated by the keys to first lock and then release or unlock the operating means and provided with locking projections for the keys, and means actuated 110 by the operating means to impart sufficient additional movement to the movable member to cause the locking projections to lock the keys.

15. In a cash-register, the combination with 115 a series of keys, of register-operating means, a movable member operated by the keys to first lock and then release the operating means and formed with locking-hooks for the keys and means actuated by the operating 120 means to impart sufficient additional movement to the movable member to cause the locking-hooks to lock the keys during the registering operation.

16. In a cash-register, the combination with 125 a series of keys, of register-operating means, a movable member adapted when operated by the movement of a key to lock all the unoperated keys in the series, means connected to said member to first lock and then release the 130 operating means when a key is operated, and means actuated by the operating means to

impart sufficient additional movement to the movable member to cause the latter to lock the operated key.

17. In a cash-register, the combination with 5 a series of keys, of a movable member arranged to be operated by said keys, an operating means, a beveled flange connected to the operating means and a beveled lug connected to the movable member and arranged to first 10 lock the operating means upon the movement of a key and then to be given an additional movement by said flange to lock the operated key during the registering operation.

18. In a cash-register, the combination with 15 a series of keys, registering-wheels and an operating mechanism, of a register throw-out device, comprising a rock-frame carrying connecting-pinions, an operating device for said frame and a lever for throwing the operating 20 device into and out of operative position, means for setting the lever by the operation

of a key and means for completely operating the lever upon the movement of the operating mechanism.

19. In a cash-register, the combination with 25 a series of keys, of a register-operating means, a latch plate or lever arranged to be struck by the keys, a register-operating means, and a locking mechanism arranged to lock the operating means during the movement of the 30 operated key, a device arranged to then lock the latch plate or lever so as to prevent the operation of any additional key until the movement of the operating mechanism is completed.

In testimony whereof I affix my signature 35 in the presence of two witnesses.

FRANK H. BICKFORD.
